THIURONIUM COMPOUNDS AS
BIOCIDAL AGENTS

Pat B. Hamilton, Chapel Hill, N.C., and Donald R. Napier, Ponca City, Okla., assignors to Continental Oil Company, Ponca City, Okla., a corporation of Delaware
No Drawing. Filed Sept. 29, 1965, Ser. No. 491,432
10 Claims. (Cl. 167—30)

ABSTRACT OF THE DISCLOSURE

Improved biocidal agents comprising bis(isothiureidomethyl) alkylaromatic dihydrohalides which have a long chain alkyl group containing at least 10 carbon atoms.

The present invention relates to a class of poly thiuronium compounds which is useful as biocidal agents. More particularly, the present invention relates to improved biocidal agents comprising bis(isothiureidomethyl) alkylaromatic dihydrohalides which have a long chain alkyl group containing at least 10 carbon atoms.

Inasmuch as thiuronium salts are easily prepared from organic halides and thiourea, and since such compounds are characterized by high crystallinity and narrow melting ranges, they have become well known in the field of qualitative organic analysis. Also, certain thiuronium compounds are known to be effective as biocidal agents. For example, U.S. Patent No. 2,999,046 to Rosen teaches a class of thiuronium compounds, similar to those of the present invention, and also teaches that such thiuronium compounds are biologically active. More specifically, he teaches that his thiuronium compounds are useful as parasiticides, insecticides, miticides, and as fungicides. The thiuronium compounds of Rosen are restricted to those containing at most 8 carbon atoms.

In addition, homologous mono thiuronium compounds are known. (U.S. Patent No. 2,640,079 to De Benneville et al. teaches such a compound.) While the mono thiuronium compounds are effective against gram positive bacteria, it has been our observation that they have only a limited activity against gram negative bacteria.

Unexpectedly, we have found that poly thiuronium compounds derived from alkylaromatic hydrocarbons having at least 10 carbon atoms in the alkyl group give a marked superiority as biocidal agents. More specifically, we have found that poly thiuronium compounds of the type hereinbefore described are superior biocidal agents to similar compounds which (1) have less than 10 carbon atoms in the alkyl group or (2) are the mono homologs.

It is an object of the present invention to provide an improved biocidal agent.

It is another object of the present invention to provide a biocidal agent which is particularly effective against bacteria which are difficult to kill.

It is still another object of the present invention to provide a biocidal agent which is particularly effective in killing gram negative bacteria.

It is a further object of the present invention to provide a method of killing bacteria which comprises subjecting the bacteria to a toxic amount of a poly thiuronium compound as described herein.

Broadly stated, the present invention relates to a composition of matter, having particular utility as a biocidal agent, and having the formula

2

wherein R is an alkyl group containing from 10 to 18 carbon atoms, preferably from 10 to 14 carbon atoms, said alkyl group being either straight or branched chain, wherein A is either hydrogen or a methyl group, wherein 5 X is halogen, which, preferably is chlorine, and wherein n is a number of from about 1.4 to about 2.8, preferably from about 1.6 to about 2.4. (The line (~~~~~) is used to indicate that more than one group can be attached.) For convenience, we refer to these compounds as "bis" thiuronium compounds.

In one aspect the invention relates to a method of killing bacteria which comprises subjecting the bacteria to contact with a toxic amount of a composition as hereinbefore described.

15 Inasmuch as the alkylaromatic portion of the thiuronium compounds of our invention is an important feature of our invention, this will be described in considerable detail. The aromatic radical of the compounds of our invention is derived from either benzene or toluene, but 20 preferably is derived from benzene. The long chain alkyl group of the alkylaromatic portion of the thiuronium compounds of our invention is either straight or branched chain. Usually, the alkyl group contains from 10 to 18 25 carbon atoms, but preferably contains from 10 to 14 carbon atoms. In addition, it is to be understood that the thiuronium compounds can be derived from mixtures of alkylaromatic hydrocarbons containing alkyl groups of varying length, as hereinbefore defined. In fact, the commercially available alkylaromatic hydrocarbons are mixtures.

An example of a particularly suitable commercially available alkylaromatic hydrocarbon which can be used to prepare the biocidal composition of our invention is a material which is known to the trade as dodecylbenzene. 35 Dodecylbenzene is available under the trade name of "Neolene" 400 from Continental Oil Company. In a typical process dodecylbenzene is prepared by first polymerizing propylene to produce a mixture of olefins which are predominantly C₁₂ (dodecene). Benzene is then alkylated with the dodecene to produce dodecylbenzene. The preparation of dodecylbenzene is described more completely in U.S. Patent 2,941,015 to Robert R. Kylander, which patent is made a part of this specification. A typical sample of dodecylbenzene has the following properties:

45	Distillation Range, ° F.	
	I.B.P.	535
	5%	545
	10%	550
	50%	560
	90%	580
	97%	592

⁴ ASTM D-156.

⁵ ASTM D-56.

70 It is generally known that the alkyl group in dodecylbenzene is branched chain. More recently, in order to produce detergents which are less resistant to attack by

bacteria, straight chain alkylaromatic hydrocarbons, similar to dodecylbenzene, have been prepared. These materials constitute a class of materials which, when sulfonated, are known in industry as biodegradable detergents. It is to be understood that any of the n-alkyl-aromatic hydrocarbons which are used in preparing biodegradable detergents and having at least 10 carbon atoms in the alkyl group can be used to prepare the biocidal agents of our invention.

The preparation of a particularly suitable n-alkyl-aromatic hydrocarbon for use in our invention is described in application Serial No. 129,252, filed August 4, 1961, and having the same assignee as the present application. For reason of convenience, this application is made a part of the present application. Briefly, application Serial No. 129,252 relates to a process of preparing a detergent alkylate wherein the process comprises the following steps, broadly stated: (a) separating a fraction of substantially straight chain C_8 - C_{18} hydrocarbons from a petroleum distillate substantially free of olefins and containing said straight chain hydrocarbons together with non-straight chain hydrocarbons, (b) chlorinating said fraction to the extent whereby between about 10 and about 35 mole percent of the straight chain hydrocarbons present are substantially only mono-chlorinated, (c) alkylating an aromatic compound, selected from the group consisting of benzene, a lower alkyl substituted benzene and mixtures thereof, with the chlorination product of step (b) in the presence of an alkylation catalyst.

n-Alkylaromatic hydrocarbons of the aforementioned type are available under the trademarks "Nalkylene" 500 and "Nalkylene" 600 from Continental Oil Company. These materials have the following typical properties:

"NALKYLENE" 500		
Test	Typical Value	Test Method
Boiling range ($^{\circ}$ F.)	535-595	ASTM D-447.
Bromine Number	0.05 max	ASTM D-1158.
Average molecular weight	231-241	Mass spec.
Color-Saybolt	+25	
Specific gravity (20/20)	0.85-0.87	ASTM D-287.
Viscosity (Saybolt seconds)	40-45 at 100° F	ASTM 88-44.

"NALKYLENE" 600		
Test	Typical Value	Test Method
Boiling range ($^{\circ}$ F.):	580-590	ASTM D-447.
5%	600-615	
95%		
Bromine Number	0.05 max	P.M. No. 21.
Average molecular weight	255-264	Mass spec.
Color-Saybolt	25 min.	P.M. No. 20.
Specific gravity	0.85-0.87	ASTM D-287.
Viscosity (Saybolt seconds)	40-46 at 100° F	ASTM 88-44.

Still another suitable alkylaromatic hydrocarbon for use in preparing the biocidal composition of our invention is a by-product of the production of a material which we refer to as "dimer alkylate." Dimer alkylate" has branched-chain alkyl groups, as does dodecylbenzene. Briefly described, dimer alkylate is prepared by the following steps:

- (1) dimerization of a suitable feedstock, such as cat poly gasoline, and
- (2) alkylation of an aromatic hydrocarbon with the dimer formed in step (1).

Briefly, the dimerization step uses a Friedel-Crafts alkylation sludge as a catalyst. This process is described in application Serial No. 367,417, filed May 14, 1964, and having the same assignee as the present application. The fraction produced by the dimer alkylate process which is suitable for use in preparing the product of this invention is that having a boiling range of about 475 to about 600 $^{\circ}$ F., preferably about 500 to about 590 $^{\circ}$ F., as determined by ASTM procedure D-86.

DESCRIPTION OF PROCESS

The first step in preparing the biocidal composition of our invention is the preparation of the poly halomethylated alkylaromatic hydrocarbon (preferably "bis" chloromethylated alkylaromatic hydrocarbon). The preparation

of these materials uses a particular chloromethylating agent which is formed by reacting formaldehyde or a compound which engenders formaldehyde with a chlorine-containing compound which will engender hydrogen chloride in the presence of an alcohol and sulfuric acid.

Suitable chlorine-containing compounds which will engender hydrogen chloride under the conditions used herein include phosphorus trichloride, phosphorus pentachloride, sulfuric oxychloride, sulfurous oxychloride, and acyl chlorides such as acetyl chloride.

Suitable alcohols are the primary monatomic saturated aliphatic alcohols containing from 1 to 4 carbon atoms, such as, for example, methanol, ethanol, normal propanol and normal butanol.

The relative amounts of the various components of the chloromethylating reagent, and the amount of chloromethylating agent used in relation to the alkaryl hydrocarbon, are shown below.

	Suitable (moles)	Preferred (moles)
Alkaryl hydrocarbon	1	1
Formaldehyde	2.1-4.0	3.4-3.6
Alcohol	2.1-4.0	3.2-3.4
Chlorine-containing compound	1.0-3.0	1.1-1.3
Sulfuric acid	2.6-6.0	4.0-5.0

The chloromethylation reaction is conducted at a temperature in the range of about 65 to about 80 $^{\circ}$ C., preferably about 66 to about 68 $^{\circ}$ C., and for a time in the range of from about 2 to about 10 hours, preferably from about 4 to about 6 hours.

Specifically, the chloromethylation procedure can be illustrated as follows: 100 grams of dodecylbenzene is prepared as follows: 42 grams of p-formaldehyde and 43 grams methyl alcohol are added to a 1-liter Morton flask which is equipped with a sealed stirrer, thermometer, and dropping funnel. The flask is placed in an ice bath and mixing is begun. Phosphorus trichloride (65.5 grams) is added dropwise from the funnel while maintaining a temperature between 29 and 32 $^{\circ}$ C. After the chloride addition, the reaction mass is aged 10 minutes at the same temperature. One hundred seventy-five grams of 100 percent sulfuric acid is then added to the dropping funnel. The sulfuric acid is then added to the reaction mass at a rate to maintain the same temperature. This is followed by post-stirring for an additional 15 minutes. This reaction mass and the dodecylbenzene are combined and heated at 67 $^{\circ}$ C. for 5 hours to produce the chloromethylated dodecylbenzene.

It should be noted that usually the halomethylation products are mixtures of homologous products containing 1, 2 or 3 halomethyl groups. Moreover, the distribution of these products varies according to the type of alkylaromatic hydrocarbon employed. Thus, while the above-identified "Neolene" 400 and "Nalkylene" 500 exhibit approximately equal reactivity in a dihalomethylation process, the product of the former is essentially all bis-derivative, whereas the product of the latter is more nearly a mixture of mono and tri derivatives.

The degree of halomethylation is the average of the number of halomethyl groups present. As indicated previously, for reason of convenience we refer to those compounds derived from materials having from about 1.4 to about 2.8 halomethyl groups, preferably from about 1.6 to about 2.4 halomethyl groups, as "bis" compounds.

The second step in the process of preparing the biocidal agents of our invention comprises reacting the bis-halomethylated alkylaromatic hydrocarbon with thiourea. The reaction is generally carried out in the presence of an inert volatile organic solvent (e.g., isopropanol). Since the reaction of the second step is well known to those skilled in the art, it is believed that further description is unnecessary.

In order to disclose the nature of the present invention

still more clearly, the following illustrative examples will be given. It is to be understood that the invention is not to be limited to the specific conditions or details set forth in these examples except in so far as such limitations are specified in the appended claims.

EXAMPLE 1

"Nalkylene" 500 and chloromethylating reagent (3.4 equivalents) prepared as outlined above were combined and heated 5 hours at 67-68° C. The crude product was separated, washed with water, dilute base and subsequently dried. Analysis of the finished product indicated at 94.5 percent yield of chloromethylated alkylbenzene containing 17.1 weight percent chlorine and having an average of 1.6 chloromethyl groups per molecule. The product was a mixture consisting essentially of mono, bis and tris halomethyl alkylbenzene together with minor amounts of diarylmethane-type condensation products.

EXAMPLE 2

Dodecylbenzylchloride derived from propylene tetramer was treated 3 hours at 75° C. with 3.4 equivalents of the above-described chloromethylating reagent. After separation, the crude product was subjected to a further identical chloromethylation. Distillation of the second product yielded a 91/9 mixture of bis and mono chloromethyl)dodecylbenzene (boiling range: 150-170° C./0.1 mm.) obtained as a viscous water-white liquid.

Refluxing 3 hours a solution of 91/9 bis-mono chloride, thiourea (10 percent excess) and isopropanol (1 part) produced the corresponding isothiuronium salts in essentially quantitative yield.

EXAMPLE 3

This example illustrates that the bis thiuronium compounds are more effective than the mono thiuronium compounds as bactericidal agents.

The hydrocarbon used was dodecylbenzene (branched chain C₁₀-C₁₄, predominantly C₁₂). This material was chloromethylated using the procedure described herein to produce a product containing 10 mole percent bis(chloromethyl)dodecylbenzene. This product was then fractionally distilled to give mono-bis(chloromethyl) dodecylbenzene mixtures with bis contents ranging from 2.5 percent to 91 percent. These products were converted to the corresponding thiuronium chlorides by heating with thiourea (5 percent excess) in 1 part isopropanol. Tests against two gram negative organisms, *Pseudomonas aeruginosa* and *Escherichia coli*, were made with five of the thiuronium preparations. The minimum inhibitory concentrations of the preparations were determined in an arithmetic dilution assay, the technique of which is well known to those versed in the art. The test medium was nutrient broth which had received a 0.1 percent inoculum of a 6-hour old culture in Difco AC Broth which had been incubated at 37° C. The assay was read after incubation at 37° C. for 42 hours. An analysis of variance was performed on the data to obtain 95 percent confidence limits.

The results obtained were as follows:

Bis/mono mole ratio	Minimum Inhibitory Conc. (p.p.m.)	
	<i>E. coli</i> (g.-)	<i>P. aeruginosa</i> (g.-)
2.5/97.5	12±1.7	1>47
3.8/96.2	7.4±0.3	1>47
10/90	5.0±0.4	31±0.9
42/58	4.0±0.4	9.7±0.5
91/9	2.0±0.2	5±0.5

¹ Approximate maximum solubility in medium.

The preceding data shows the following:

- (1) An increasing amount of bis thiuronium compounds gives an increasing activity against a gram negative organism.
- (2) The activity of these products against *P. aeruginosa*, an organism known for its resistance to the usual anti-

bacterial agents, was due primarily to the bis thiuronium compound.

EXAMPLE 4

This example illustrates the superior bactericidal effects of the compounds of our invention as compared to similar materials.

The compounds of our invention which were tested had the following formulas

Compound A

*From propylene tetramer.

**Contained 91 percent bis.

Compound B

*From propylene tetramer.

**Contained 96 percent bis.

The compounds, tested for comparison, had the following formulas

Compound C

*From propylene tetramer.

**Contained 91 percent bis.

Compound D

*From propylene tetramer.

Compound E

*From propylene tetramer.

Using the arithmetic dilution technique described in Example 3, the following results were obtained.

Bacteria	Compounds				
	Minimum Inhibitory Concentration, p.p.m.				
	A	B	C	D	E
<i>B. cereus</i> (g.+)	2	2	16	3	2
<i>S. aureus</i> (g.+)	2	1	4	1	1
<i>P. fluorescens</i> (g.-)	5	16	47	33	37
<i>P. aeruginosa</i> (g.-)	5	10	47	28	28
<i>E. coli</i> (g.-)	2	2	23	6	12
<i>S. typhosa</i> (g.-)	2	2	16	5	8
<i>P. vulgaris</i> (g.-)	3	3	3	7	7

EXAMPLE 5

This example illustrates the superior bactericidal properties of the compositions of our invention as compared

to the compounds suggested by Rosen. The compounds tested had the following formulas

Compound F

(Material of our invention.)

*n-Type.

Compound G

(A material suggested by Rosen.)

Compound H

(A material suggested by Rosen.)

*n-Type.

Using the arithmetic dilution technique described in Example 3, the following results were obtained:

Amount of Compound (p.p.m.)	Compound F		Compound G		Compound H	
	P. f.	S. a.	P. f.	S. a.	P. f.	S. a.
50	—	—	+	+	—	—
41	—	—	+	+	—	—
33	—	—	+	+	—	—
23	—	—	+	+	—	—
16.6	—	—	+	+	+	—
9	—	—	+	+	+	—
6.5	—	—	+	+	+	—
4.7	—	—	+	+	+	—
2.9	+	—	+	+	+	—
2	+	—	+	+	+	—
1	+	—	+	+	+	+

+=Growth at indicated concentration of compound.

—=No growth.

P. f.=*Pseudomonas fluorescens*.

S. a.=*Staphylococcus aureus*.

The above data shows that the C₁₂ compound of our invention is at least 50 fold better than the C₁ compound suggested by Rosen. It also shows that the C₁₂ compound is superior to the C₈ compound in controlling the gram negative organism *Pseudomonas fluorescens* by a factor of about 5 to 1. It is well known to those skilled in the art that gram negative organisms and particularly pseudomonads are highly resistant to most antimicrobial agents. Hence, the improvement shown by the compound of our invention is highly significant.

While particular embodiments of the invention have been described, it will be understood, of course, that the invention is not limited thereto, since many modifications may be made; and it is, therefore, contemplated to cover by the appended claims any such modifications as fall within the true spirit and scope of the invention.

The invention having been described, what is claimed and desired to be secured by Letters Patent is:

1. A composition of matter, suitable for use as a biocidal agent, having the formula

wherein R is an alkyl group containing from 10 to 20 carbon atoms and which is straight or branched chain, A is either hydrogen or a methyl group, X is a halogen, and n is a number of from about 1.4 to about 2.8.

5 2. A composition of matter as described in claim 1 characterized further in that X is chlorine.

3. A composition of matter as described in claim 2 characterized further in that R is an alkyl group containing from 10 to 14 carbon atoms.

10 4. A composition of matter as described in claim 3 characterized further in that n is a number of from about 1.6 to about 2.4.

5. A composition of matter, suitable for use as a biocidal agent, having the formula

20 wherein R is an alkyl group containing from 10 to 14 carbon atoms and n is a number of from about 1.6 to about 2.8.

6. A composition of matter, suitable for use as a biocidal agent, having the formula

25 wherein n is a number of from about 1.4 to about 2.8, X is a halogen, and the multivalent radical

is derived from dodecylbenzene produced by the polymerization of propylene.

40 7. A method of killing bacteria which comprises subjecting the bacteria to contact with a toxic amount of a composition of matter having the formula

45 wherein R is an alkyl group containing from 10 to 20 carbon atoms and which is straight or branched chain, A is either hydrogen or a methyl group, X is a halogen, and n is a number ranging from about 1.4 to about 2.8.

8. A method of killing bacteria as described in claim 7 characterized further in that X is chlorine.

45 9. A method of killing bacteria as described in claim 8 characterized further in that R is an alkyl group containing from 10 to 14 carbon atoms.

10. A method of killing bacteria as described in claim 9 characterized further in that n is a number of from about 1.6 to about 2.4.
